LANCELOT KIRKUP, OF BROOKLYN, NEW YORK, ASSIGNOR TO HIMSELF.
ALBERT PALMER, JOEL PARKER, AND W. M. HUDSON.

Letters Patent No. 60,745, dated January 1, 1867.

IMPROVEMENTS IN ANVILS.

The Schedule referred to in these Letters Patent and making part of the same.

TO ALL WHOM IT MAY CONCERN:

Be it known that I, LANCELOT KIRKUP, of Brooklyn, Kings county, New York, have invented, made, and applied to use, certain new and useful improvements in the Construction of Anvils; and I do declare the following to be a full, clear, and correct description of the same, reference being had to the accompanying drawings, making part of this specification, and to the letters of reference marked thereon, in which—

Figure 1 is a side elevation of my improved anvil.

Figure 2, a top view of the same.

In the drawings, like parts of the invention are indicated by the same letters of reference.

The nature of my invention consists in constructing an anvil as hereinafter fully shown. The object of my invention is to produce an anvil more durable than the anvil now in use, and one more readily and economically manufactured.

To enable those skilled in the arts to make and use my invention, I will describe the same.

A shows the upper section of an anvil, and B the lower section of the same; which sections A and B may be firmly united by the bolts or keys C C, or in any convenient manner. The upper section, A, of the anvil, is made of cast steel, in one piece, or of steel without any welding, instead of welding the ears and other parts separately on to the core, as in the ordinary mode of manufacture. The upper surface or face of this upper section is made larger in area, but smaller in depth, making the same less weighty and more portable, and, when placed upon the lower section or block B, affording the same area of top as an anvil made in the ordinary way, but weighing twice as much. The lower section or block, B, may be made of cast iron or any suitable metal, having the ends of its upper surface inclined slightly to receive the upper section or cast-steel portion, A, fitting snugly upon the same. C C show bolts or keys passing through the section B and the section A, to retain the same in position upon the section B.

The great advantage arising from the construction of an anvil as described, is that the upper section upon which the work is done is or may be made of solid steel, while the lower portion may be made of such cheap material as to make the perfect anvil no more expensive than those ordinarily used, but very much more durable.

Having thus described my invention, what I claim as new, and desire to secure by Letters Patent, is—
The anvil constructed substantially as shown for the purposes specified.
